(57) **CLAIM**

The ornamental design for a tailgate cargo enclosure, as shown and described herein.

DESCRIPTION

The claimed tailgate cargo enclosure is used to extend the cargo bed of a vehicle and could be mounted on a truck.

FIG. 1 is a perspective view of a tailgate cargo enclosure illustrating our new design mounted on a rear portion of a

vehicle utilizing fastening and/or support means such as straps. The vehicle and the straps are shown in phantom for illustration purposes only and form no part of the claimed design.

FIG. 2 is a front perspective view of the tailgate cargo enclosure of FIG. 1.

FIG. 3 is a rear elevational view of the tailgate cargo enclosure of FIG. 1.

FIG. 4 is a front elevational view of the tailgate cargo enclosure of FIG. 1.

FIG. 5 is a top plan view of the tailgate cargo enclosure of FIG. 1.

FIG. 6 is a bottom plan view of the tailgate cargo enclosure of FIG. 1.

FIG. 7 is a left side view of the tailgate cargo enclosure of FIG. 1;

FIG. 8 is a right side view of the tailgate cargo enclosure of FIG. 1;

FIG. 9 is a perspective view of a second embodiment of a tailgate cargo enclosure illustrating our new design mounted on a rear portion of a vehicle utilizing fastening and/or support means such as straps. The vehicle and the straps are shown in phantom for illustration purposes only and form no part of the claimed design. In the embodiment of FIG. 9, generally vertical connection members are shown in phantom for illustration purposes only and form no part of this embodiment of the claimed design.

FIG. 10 is a front perspective view of the tailgate cargo enclosure of FIG. 9.

FIG. 11 is a rear elevational view of the tailgate cargo enclosure of FIG. 9.

FIG. 12 is a front elevational view of the tailgate cargo enclosure of FIG. 9.

FIG. 13 is a top plan view of the tailgate cargo enclosure of FIG. 9.

FIG. 14 is a bottom plan view of the tailgate cargo enclosure of FIG. 9.

FIG. 15 is a left side view of the tailgate cargo enclosure of FIG. 9; and,

FIG. 16 is a right side view of the tailgate cargo enclosure of FIG. 9.
